UNITED STATES PATENT OFFICE.

EDMOND W. T. RICHMOND, OF ROMFORD, ENGLAND.

DESIGN FOR A HOT CLOSET AND CARVING-TABLE.

SPECIFICATION forming part of Design No. 33,929, dated January 15, 1901.

Application filed December 21, 1900. Serial No. 40,690. Term of patent 7 years.

To all whom it may concern:

Be it known that I, EDMOND WALTER TYRRELL RICHMOND, a subject of the Queen of Great Britain, residing at Summercourt, Romford, Essex county, England, have invented and produced a new and original Design for a Gas Hot Closet and Carving-Table, of which the following is a specification.

The accompanying drawing shows a perspective view of a hot closet and carving-table embodying my design.

The leading features of the design are the rectangular body portion A, the end of which is ornamented by a single panel B having the general contour and appearance shown, with a central ornamental figure C. The front of the stove is divided into three sections having like ornamental panels D with the similar central figures. These three panels are, in fact, doors and have at their sides hinge or handle projections consisting of forwardly-projecting plates or brackets E, connected by a cylindrical piece F. At the corners of the

body are ornamental column-like parts G, having ornamental vertically-extending panels or grooves H and enlarged parts I at top and bottom, formed with a molding effect corresponding with like straight moldings K, running along the top and bottom edges of the rectangular frame.

L M N are three curved inverted covers applied on the top of the rectangular body, the upper face of which is flat except at one end, where there is a raised rectangular box-like body O.

I claim—

The design for a hot closet and carving-table substantially as herein shown and described.

In testimony whereof I have hereunto subscribed my name.

EDMOND W. T. RICHMOND.
